ELECTROMAGNETIC DEVICE

Martin Joos, Alma Center, Wis., and Bethel J. Babbitt, Riverside, Ill., assignors to Western Electric Company, Incorporated, New York, N. Y., a corporation of New York

Application January 13, 1933, Serial No. 651,488

19 Claims. (Cl. 175—183)

This invention relates to an electromagnetic device and more particularly to an electrical measuring device.

In measuring the magnetic properties of highly permeable magnetic materials, the difficulties of obtaining accurate results increase with higher permeabilities.

An object of the present invention is to provide an accurate and efficient electromagnetic device.

10. In accordance with one embodiment of the invention, a permeameter or induction meter is provided having a rotatable detector responsive to the leakage flux from two points on the specimen being measured, in which the detector and the portion of the specimen being measured are enclosed in a magnetic shield having means for eliminating remanence and reducing hysteresis losses. The permeameter is provided with a yoke of a nickel-iron alloy having distributed air gaps whereby high initial permeability and low coercive force are attained and the yoke is provided with a winding for equalizing the time constants of the windings on the yoke and the magnetizing and induction windings in order to obtain a true 15 reading of induction.

A complete understanding of the invention may be had by reference to the following description taken in conjunction with the accompanying drawings, in which

30. Fig. 1 is a perspective view partly in section illustrating an embodiment of the invention; and

Fig. 2 is a circuit diagram of the apparatus illustrated in Fig. 1.

The apparatus may be mounted on a base 6 provided with a cover or casing 7 hinged to the base along the back side. Mounted upon the base is a U-shaped yoke 8 consisting of a plurality of laminations of a magnetic material having a high initial permeability and low coercive force, such as a nickel-iron alloy. The yoke is U-shaped in form and each leg of the yoke forms in effect a section. These sections are preferably individually mounted on the base and arranged in abutting relation so as to provide a minute air gap between the sections. The low coercive force, together with the distributed air gaps in the yoke, produces a low remanence or residual magnetism in the yoke.

50. The open ends of the yoke are provided with pole pieces 9 having apertures 11 therein and a sleeve 12 of non-magnetic material, such as brass or cardboard, extends from an aperture in one pole piece to the other. The sleeve is adapted to receive therein a specimen 13 to be measured and surrounding the sleeve is a magnetizing wind-

ing 14 for applying a magnetomotive force to the specimen. In order to provide a good magnetic contact between the pole pieces and the specimen, a clamp 15 is provided in the aperture 11 of each pole piece and this clamp is urged upwardly by a pair of helical springs 16. In order to separate the clamp to permit the insertion of the specimen, the yoke is provided with a pair of vertical apertures through which a staple 17 extends to contact with the top face of the clamp to urge the clamp downwardly until the end of the specimen is inserted between the clamp and the pole piece. The yoke is provided with a compensating winding 18, which is preferably made in a number of sections, one section being applied to each leg of the yoke.

55. Superimposed upon the magnetizing winding 14 and co-axial therewith is an induction winding 19, which is preferably located centrally of the magnetizing winding, and a pair of pole pieces 21 extends to points of the magnetizing winding adjacent the ends of the induction winding. The inner ends of these pole pieces are arcuate and an armature 22 is adapted to rotate therebetween. The armature consists of a core 20 of magnetic material having a high initial permeability, such as a nickel-iron alloy, and the core is provided with an armature winding. The armature is supported on the shaft 23 which may be rotated by means of a motor 24. In order 30 to eliminate the effect of stray flux, the armature, as well as the induction coil and that portion of the magnetizing winding containing the portion of the specimen to be measured, is enclosed in a magnetic shield 25. This shield is preferably 35 made of two parts, as shown in the drawings, the lower part being secured to the base 6 and the upper part being attached to the casing by means of bolts 26 so that in raising the casing the shield will be separated and provide access 40 to the armature 22. The shield is made of a magnetic material having a high initial permeability, such as a nickel-iron alloy, and in order 45 to prevent magnetization from the shield itself, the shield is continuously demagnetized. This is 50 accomplished by providing the shield with a plurality of apertures 27 extending over the entire shield. The conductors of an alternating current winding, preferably a three phase winding, are 55 threaded back and forth through the apertures and by passing an alternating current through the winding, a continuous demagnetizing force is applied to the shield. The pole pieces 21 of the detector unit are also preferably similarly

equipped with a demagnetizing winding threaded through apertures in the pole pieces.

When there is a difference in magnetic potential at the ends of pole pieces 21 which are adjacent the specimen being measured, a current will be generated in the detector coil of armature 22 which is led through slip rings 28 to an input circuit 29 of a thermionic tube amplifier, the output circuit 31 of which is connected to a second pair of slip rings 32 also on shaft 23. This shaft 10 also carries a two-part commutator 33 and one of the slip rings 32 is connected to one part of the commutator and the other slip ring 32 to the other part of the commutator. The commutator rectifies the current delivered from the amplifier and directs it to a galvanometer 34.

In measuring the permeability of a specimen, the specimen to be measured is placed within the magnetizing winding and clamped between the pole pieces. In order to apply a magnetomotive force to the specimen, a source of direct current energy 35 is provided having an ammeter 36 and a variable resistance 37 in circuit therewith. The source of energy may be connected to the magnetizing winding by closing a gang switch 38, 25 a reversing switch 39 and closing a switch 41 on its upper contacts. The first step in measuring the inductance consists in demagnetizing the specimen. This is accomplished by adjusting the resistance 37 so as to cause a rather high current 30 to flow through the magnetizing winding and intermittently reversing switch 39. The current is then reduced by adjusting resistance 37 and the current is again reversed a number of times. This process is continued until the current is reduced to zero. The motor 24 is then started and resistance 37 is then set so as to allow a current 35 to flow which will provide a magnetomotive force at which the specimen is to be tested. A switch 42 is then closed which causes a current to be 40 applied to the compensating winding 18 from a direct current source 43 having an ammeter 44 in circuit therewith through one of the variable resistances 45 and 46, depending upon which contacts the gang switch is closed upon. The resistance 45 or 46 is then varied until the galvanometer 34 reads zero, at which time the magnetic potential drop in the portion of the specimen being tested will be equal to the magnetomotive force applied to this portion of the specimen, and at 50 this time there will be no difference of potential at the points on the magnetizing winding at which the pole pieces 21 engage therewith and, therefore, no leakage flux in the armature field. The gang switch 38 is then reversed, which reverses 55 both the magnetizing current and the compensating current. The compensating current is then again adjusted by means of the resistance 45 or 46 until the galvanometer 34 reads zero. It has been found that the resistances 45 and 46 60 are not necessarily equal and in fact usually vary when the adjustment is such that a reversal of the gang switch causes no deflection in the galvanometer 34. This is due to the residual induction in the yoke which is largely overcome by repeated reversals of the gang switch. After the apparatus is adjusted so that the magnetic potential drop in the portion of the specimen being measured is equal to the magnetomotive force applied thereto, the gang switch is reversed and the energy in the induction of the specimen is applied to the induction winding 19, the magnitude of which is indicated by a galvanometer 47 in circuit therewith.

It is evident that if the time constants of the

induction winding and the winding on the yoke are not equal, the galvanometer 47 will not always indicate the true induction in the specimen. This difficulty is overcome by providing an equalizing winding 48 on the yoke which has a variable resistance 49 in circuit therewith. This resistance may be varied until the time constants 5 of the induction winding and the yoke windings are equal.

In plotting an induction curve of a specimen, 10 it may be necessary to have available a larger scale than is provided by galvanometer 47. For this purpose a switch 51 is provided which, when closed on its upper contacts, provides a direct connection between the circuit of the induction 15 coil and the galvanometer and when this switch is on its lower contacts, a known or predetermined resistance is placed in the galvanometer circuit to place the galvanometer on a different scale. 20

It may at times become necessary to check the the operation of galvanometer 47. For this purpose a mutual inductance 52 is permanently placed in the galvanometer circuit so that its effect will be the same during calibration as in 25 the actual use of the galvanometer with the apparatus. The switch 41 when closed on its lower contacts connects the mutual inductance to the source of energy 35 and by reversing the switch 39 a transient current similar to that used in 30 measuring is applied to the galvanometer.

It will be understood that the nature and embodiment of the invention herein described is merely illustrative and that many changes and modifications may be made therein without departing from the spirit and scope of the invention. 35

What is claimed is:

1. A measuring apparatus comprising means for impressing a magnetomotive force on a specimen equal to the magnetic potential drop in the specimen, means for determining the equality of said quantities including an armature rotatable in the leakage flux of the specimen and having a core of high initial permeability, and means for 40 measuring the magnetic induction in the specimen. 45

2. A measuring apparatus comprising means for impressing a magnetomotive force on a specimen equal to the magnetic potential drop in the 50 specimen, means for determining the equality of said quantities including an armature rotatable in the leakage flux of the specimen and having a core of a nickel-iron alloy of high initial permeability, and means for measuring the mag- 55 netic induction in the specimen.

3. A measuring apparatus comprising means for impressing a magnetomotive force on a specimen equal to the magnetic potential drop in the specimen, a rotatable armature having a core 60 of magnetic material, a pair of pole pieces adjacent the armature and extending to points adjacent the ends of the portion of the specimen being measured, indicating means associated with the armature to indicate the amount of 65 leakage flux from said points of the specimen, and means for indicating the magnetic induction in the specimen.

4. A measuring apparatus comprising a yoke of magnetic material having distributed air gaps, 70 a compensating winding on the yoke, a winding extending across the ends of the yoke for receiving a specimen to be measured, and means for measuring the induction in the specimen.

5. A measuring apparatus comprising a yoke 75

- of a nickel-iron alloy having a high initial permeability and provided with distributed air gaps, a compensating winding on the yoke, a winding extending across the ends of the yoke for receiving a specimen to be measured, and means for measuring the induction in the specimen. 5
6. A measuring apparatus comprising a yoke of magnetic material having an air gap, a compensating winding on the yoke, a winding extending across the ends of the yoke for receiving a specimen to be measured, and means for measuring the induction in the specimen. 10
7. A measuring instrument comprising a magnetizing coil for receiving a specimen to be measured, an induction coil co-axial therewith, a magnetic shield enclosing the portion of the specimen to be measured, and means for demagnetizing the shield. 15
8. In an electromagnetic device, means affected by magnetic lines of force, a shield for said means, and means for demagnetizing the shield. 20
9. In an electromagnetic device, means affected by magnetic lines of force, a shield for said means, and means for applying an alternating magnetic flux to the shield to maintain the shield demagnetized. 25
10. In an electromagnetic device, means affected by magnetic lines of force, a shield for said means, said shield having a plurality of apertures, and insulated conductors passing through said apertures for receiving a demagnetizing current. 30
11. A measuring instrument comprising a magnetizing coil for receiving a specimen to be measured, a pole piece in close proximity to a point on said winding, and an armature rotatable in the magnetic flux from said pole piece to measure the magnetic leakage from said point. 35
12. A measuring instrument comprising a magnetizing coil for receiving a specimen to be measured, a pole piece in close proximity to a point on said winding, an armature rotatable in the magnetic flux from said pole piece to measure the magnetic leakage from said point, and means for applying a demagnetizing force to the pole piece. 40
13. A measuring instrument comprising a magnetizing coil for receiving a specimen to be measured, an armature, and pole pieces adjacent the armature and extending to spaced points on the winding. 50
14. A measuring instrument comprising a magnetizing coil for receiving a specimen to be measured, an armature, pole pieces adjacent the armature and extending to spaced points on the wind- 55
- ing, and means associated with the pole pieces for preventing remanence and reducing hysteresis losses therein. 5
15. A measuring instrument comprising a yoke, a compensating winding thereon, a magnetizing winding for receiving a specimen to be measured, an induction winding co-axial with the magnetizing winding, a movable induction type detector for leakage flux from the specimen, an amplifier associated with the detector, and an indicating device operable by said amplifier. 10
16. A measuring instrument comprising a magnetizing winding for receiving a specimen to be measured, a yoke subtending the ends of said winding, a compensating winding on the yoke to compensate for the magnetic potential drop in the specimen produced by the magnetizing winding, an induction winding co-axial with the magnetizing winding, and a winding on the yoke having a variable resistance in circuit therewith for equalizing the time constant of the windings on the yoke with the time constant of the magnetizing and induction windings. 15
17. A measuring instrument comprising a magnetizing winding for receiving a specimen to be measured, a yoke subtending the ends of said winding, a compensating winding on the yoke, a source of energy for the compensating winding, a switch for reversing the direction of current in the compensating winding, and a pair of resistances, one of which is in the compensating winding circuit for one direction of current flow and the other of which is in the compensating winding circuit for the other direction of current flow. 20
18. A measuring instrument comprising means for impressing a magnetomotive force on a specimen equal to the magnetic potential drop in the specimen, an armature rotatable in the leakage flux of the specimen for determining the equality of said quantities, a pair of slip rings connected to said armature, an amplifier connected to said slip rings, a rectifier for rectifying the output of said amplifier, said rectifier being rotatable with said armature, and an indicator operable in response to said rectified current. 25
19. A measuring instrument comprising means for impressing a magnetomotive force on a specimen equal to the magnetic potential drop in the specimen, an armature rotatable in the leakage flux of the specimen for determining the equality of said quantities, means for amplifying the current generated in said armature, and an indicating device responsive to said amplified current. 30
